D. STEINER

FLOAT OPERATED CIRCUIT CLOSER FOR OIL LEVEL ALARM DEVICES

Filed May 28, 1925

Inventor
Daniel Steiner.

By *Clarance A. D. Brian.*
Attorney

UNITED STATES PATENT OFFICE.

DANIEL STEINER, OF OLYMPIA, WASHINGTON.

FLOAT-OPERATED CIRCUIT CLOSER FOR OIL-LEVEL ALARM DEVICES.

Application filed May 28, 1925. Serial No. 33,419.

The present invention relates to an oil level alarm device, and has for its principal object to provide a device of this nature which will maintain a closed circuit so as to keep an electric light lit when the oil is above a certain predetermined level, but when the oil recedes below this level, the circuit will be broken and the light will go out, thereby indicating that the oil in the crank case should be replenished.

Another important object of the invention is to provide a device of this nature which is exceedingly simple in its construction, one which is thoroughly reliable and efficient in use, and otherwise well adapted for the purpose for which it is designed.

In the drawing:—

The figure is a sectional view through the device showing the same attached to a crank case.

Referring to the drawing in detail it will be seen that 1 designates a crank case which is provided with the usual threaded opening 2 wherein is usually engaged a pet cock. My device, however, is provided with a threaded nipple 3 which engages in this opening 2. The reservoir 4 of the device is attached to the nipple being preferably formed integral therewith and is provided with a threaded opening 5 for receiving the pet cock 6 which was taken from the opening 2, or another smaller pet cock, so that the oil may be drained if desired.

The bottom of the reservoir 4 is provided with an opening 7. A closure 8 is provided for the top of the reservoir, and has a stem 9 depending therefrom and extending through the opening 7 in order that a nut 10 may be engaged on the lower end thereof for holding the closure firmly on the upper open end of the reservoir. An annular float member 11 is disposed about the stem 9 within the reservoir 4 and has a contact 12 fixed thereto for engagement with a contact 13 which extends through insulation 14 provided in the closure 8 and terminates at its upper end in a terminal 15 to which the wire 16 may be attached. The wire 16 has an incandescent

bulb 17 therein and is connected to the source of electrical energy 18 which is grounded as at 19 preferably to the crank case. It will therefore be seen that when the oil is above the level of the reservoir 4 the float will be in a raised position and the contact 12 will be in engagement with the contact 13 to maintain the circuit just described closed, whereby the incandescent bulb 17 will be lighted. Should the oil in the crank case 1 recede below the level just indicated, the float 11 will recede in the reservoir 4, thereby separating the contact 12 from the contact 13 so as to break the circuit and the incandescent bulb will therefore go out. It will then be time to replenish the oil in the crank case.

It is thought that the construction, operation, and utility of the device will now be clearly understood without a more detailed description thereof. It is apparent that changes in the details of construction, and in the combination and arrangement of parts may be resorted to without departing from the spirit or scope of the invention as hereinafter claimed or sacrificing any of its advantages.

Having thus described the invention, what I claim as new and desire to secure by Letters Patent is:—

A float operated circuit closer including, in combination, a reservoir having its upper end open, means projecting laterally from the bottom portion of the reservoir for communicating said reservoir with a crank case, a closure for the upper end of the reservoir including a stem extending through an aperture in the bottom of the reservoir, a nut engaged with the lower end of the stem and abutting the outside of the bottom of the reservoir for holding the closure on the reservoir, a float in the reservoir of ring construction disposed about the stem to be guided thereby, a contact on the float, a second contact on the closure for engagement with the first contact.

In testimony whereof I affix my signature.
DANIEL STEINER.
